UNITED STATES PATENT OFFICE.

JOSEPH MAZER, OF SOUTH McALESTER, INDIAN TERRITORY.

WINDING-INDICATOR FOR WATCHES.

SPECIFICATION forming part of Letters Patent No. 790,512, dated May 23, 1905.

Application filed August 17, 1904. Serial No. 221,131.

To all whom it may concern:

Be it known that I, JOSEPH MAZER, a resident of South McAlester, Indian Territory, have invented a new and useful Improvement 5 in Watches; and I do hereby declare the following to be a full, clear, and exact description thereof.

My invention relates to an attachment for watches, clocks, and the like which is designed to indicate the extent to which the mainspring is wound, so that the observer 10 may know not only when the spring is fully wound or when it has run down, but also the extent to which it is wound at any particular 15 moment, and the time when it will require rewinding.

In fusee or English-lever watches the winding-arbor turns one way when the watch is being wound and the opposite way when the 20 watch is running, so that it is a simple matter to apply a winding-indicator thereto, it only being necessary to provide a train leading directly from the winding-arbor to the indicator-shaft, which train, arbor, and indicator- 25 shaft turn one way when the watch is being wound and the opposite way when the watch is running; but in watches in which the winding-arbor after the watch has been wound remains stationary while the ordinary train of 30 the watch is driven from the mainspring-barrel it has been difficult to employ a winding-indicator. It is not easy in such watches to design mechanism which will move the indicator when the watch is running to indicate 35 the extent to which the spring is unwound and which will bring the indicator back to zero when the watch is being wound.

It has been attempted to apply winding-indicators in several ways to watches provided 40 with going or safety barrels. Most of the mechanisms for this purpose have included in the train of gearing either a yielding or friction element which will slip when the watch is being wound or said train included 45 means whereby it could be connected to and disengaged from the winding-arbor and going-barrel. In the last form of mechanism the train of gearing is necessarily complicated, and with either form of gearing there

is always liability that the parts will not 50 come back accurately to the original position—that is, either by a slip in the friction element or by the teeth of the disengageable gearing not always coming into correct mesh. As a result it is not certain in winding the watch 55 that the indicator will be brought back to zero. It has also been attempted to apply a winding-indicator to a watch of the character named by using planetary gearing mounted on the barrel and arranged in the train between 60 the indicator and the winding-arbor. The difficulty with this arrangement is that the indicator will not be moved at the same speed when winding as when the watch is running, this being due to the fact that while 65 the watch is running the planetary gearing moves around with the barrel. As a result the indicator is moved a different distance while the watch is running than it is while winding, so that the indicator will not be 70 brought back to zero. Other attempts to apply winding-indicators to watches provided with a safety or going barrel have resulted in complicated trains of gearing and generally a pair of trains were necessary, one 75 operating during winding and the other while running.

The object of my invention is to provide a winding-indicator for watches or clocks provided with a going or safety barrel in which 80 the foregoing defects are overcome and in which a simple train of gearing is employed and so arranged that it will insure the indicator being brought back exactly to zero when the watch or clock is wound. 85

To these ends my invention consists, generally stated, in providing a single train of gearing between the going-barrel and winding-arbor on the one hand and the indicator on the other, which train is positive and non-yielding, is constantly in connection and never disengaged, and which will insure the indicator being moved to the same distance when winding as when running.

In the accompanying drawings, Figure 1 is 95 a face view of a watch, showing a winding-indicator. Fig. 2 is a face view of the mechanism with the dial and parts of the plate

broken away. Fig. 3 is a section on the line 3 3, Fig. 2; and Fig. 4 is an enlarged view of the indicator-dial.

In the drawings, 1 indicates the dial of the watch; 2, the bottom plate of the movement; 3, the winding-arbor, and 4 the going-barrel, in which the mainspring 5 is inclosed, with its inner end secured to the winding-arbor and its outer end to the going-barrel. The 10 going-barrel is provided on its periphery with the gear-teeth 6, which engage with the usual train and drive the watch in the ordinary way. Only a portion of such watch-train is indicated on the drawings, and as the 15 same has the ordinary mode of operation and has no bearing on the invention claimed in this application it will not be described.

The winding-arbor 3 may be turned in winding the watch in any suitable way. In 20 the drawings a well-known form of stem-winding watch is shown. The winding-shaft 7 is provided with a gear 8, engaging the usual crown-gear 9, and this is connected by an intermediate gear 10 to the ratchet-wheel 11, 25 secured to the winding-arbor 3. A spring-pressed pawl 12 engages the teeth of the ratchet-wheel in a well-known manner, preventing the same from turning backward.

The dial 1 has on its face the small dial 14, 30 which is marked with suitable designations—as, for instance, from zero ("0") to "24" and also with the words "Wind up"—and over which travels the indicator-hand 15. This dial may be located on any portion of the 35 main dial of a watch; but in the drawings it is shown as concentric with the seconds-dial, the seconds-hand being shown at 16 and connected to an arbor 17, having thereon a gear 18, driven from the usual watch-train. 40 The indicator-hand 15 is mounted on the upper end of a sleeve 19, surrounding the arbor 17 and being provided with a pinion 20 for rotating the same.

The ratchet-wheel 11 and going-barrel 4 45 are provided on their facing sides with snail-teeth 21, which snail-teeth are identical—that is, both right-hand or both left-hand; but inasmuch as they are placed opposite to each other they will, in effect, run in opposite 50 directions. Interposed between and engaging both snail-gears is a rolling member 22, which is formed as an ordinary spur-gear set perpendicularly with reference to the snail-gears and having its teeth engaging both. 55 To this rolling gear is connected a rod or arm 23, which is provided at its outer end with a rack 24, which will engage a suitable pinion, such as the pinion 20 of the indicator-sleeve or other pinion suitably geared to said indicator-sleeve. As shown in the drawings, the 60 arm 23 is mounted to reciprocate, being guided in suitable hangers 25, connected to the bottom plate of the movement. The arm 23 and the openings in the hangers 25 are either

square or of other shape other than round, 65 so that said arm is prevented from turning, thus holding the rolling gear 22 in upright position.

The operation of this mechanism is as follows: When the watch is being wound, the 70 ratchet-wheel 11 is the relatively movable part, while the barrel 4 becomes the relatively stationary part. As a consequence the snail-tooth 21 on the ratchet-wheel engaging the teeth of the gear 22 will roll the same along 75 over the snail-teeth on the barrel, thus moving said gear outwardly toward the peripheries of the barrel and ratchet-wheel and reciprocating the arm 23 and rack 24. The latter rotates the pinion 20, thus moving the indicator-hand 15 over the dial from "24" back to "0." When the watch is running, the ratchet-wheel becomes the relatively stationary part and the barrel the relatively movable part, and as a result the snail-tooth on 80 the latter will cause the gear 22 to roll over the snail-gear on the ratchet-wheel and move the same toward the center of said gears, thus through the bar 23 and rack 24 rotating the indicator in the opposite direction—that is, 85 from "0" to "24"—and if the watch is not then wound over the words "Wind up" this will indicate to the observer that the watch must be wound up.

It is important that the wheel 22 move outward or away from the centers of the barrel and ratchet-wheel during winding. If said gear moved inwardly or toward the centers of the barrel and ratchet-wheel during winding, there would be opportunities for destroying the mechanism—as, for instance, if the mainspring should break or slip during winding the ratchet-wheel would continue to turn and carry the gear 22 inwardly against the barrel-arbor and result in destroying the teeth 100 on gear 22. Therefore moving the gear 22 outwardly while winding and inwardly when the watch is running is the most practical arrangement. The reverse arrangement could be employed if the snail-teeth were removed 105 at the centers of the barrel and ratchet-wheel, so that the gear 22 could not be moved inwardly against the barrel-arbor, or if suitable stop-works were employed to secure the same result. Neither of these alternative arrangements possesses the advantages of the arrangement shown in the drawings; but I wish 110 it understood that they are not excluded by the terms of the claims.

The mechanism described is exceedingly 115 simple, requiring few additional parts to an ordinary watch, and the movement is positive in both directions, no yielding or disengageable elements being employed. As a consequence the indicator-hand will always 120 be brought back exactly to zero and will be moved through equal distances in both directions.

Numerous modifications may be made in the details of my invention without departing from the principle thereof. The bar 23 instead of having a sliding or reciprocating movement may be pivoted and have an oscillating movement, in which event the rack member 24 would be curved in an arc struck about the pivotal point of the bar 23. It is also not necessary that the snail-gears 21 be formed on the ratchet-wheel and head of the barrel, although for simplicity this is preferred. They may be formed upon other rotating disks driven the one from the arbor and the other from the barrel.

15 Instead of using a going-barrel such as illustrated, and in which the entire barrel rotates during the running of the watch, my invention can be applied equally as well to what is known as a "safety-barrel," wherein 20 the barrel itself does not rotate, but only the head thereof, to which head the inner end of the mainspring is connected. Inasmuch as the gearing in my invention is attached only to the head of the barrel, it can be applied in 25 exactly the same manner to the rotary head of the safety-barrel. I intend, therefore, by the term "barrel" as used in my claims to include not only the going-barrel illustrated, but also a safety-barrel.

30 My invention may be applied to any spring-driven mechanism, as well as to watches and clocks.

What I claim is—

1. In a watch or the like, the combination 35 with a mainspring, and barrel and arbor connected to the opposite ends thereof, of an indicator to show the condition of the mainspring, two oppositely-facing snail-gears connected to rotate the one with the arbor and 40 the other with the barrel, and gearing engaged by both snail-gears and connected to the indicator.

2. In a watch or the like, the combination 45 with the mainspring, and barrel and arbor connected to the opposite ends thereof, of an indicator to show the condition of the mainspring, two oppositely-facing snail-gears connected to rotate the one with the arbor and the other with the barrel, a rolling gear inter- 50 posed between and engaging both snail-gears, and an indicator-actuating means connected to said rolling gear.

3. In a watch or the like, the combination 55 with the mainspring, and barrel and arbor connected to the opposite ends thereof, of an indicator to show the condition of the mainspring, two opposite-facing snail-gears connected to rotate the one with the arbor and the other with the barrel, a rolling tooth- 60 gear interposed between and engaging both snail-gears, a rack-bar connected to said rolling gear, a pinion engaged by said rack-bar, and connecting means between the indicator and said pinion.

4. In a watch or the like, the combination 65 with a mainspring, and barrel and arbor connected to the opposite ends thereof, of an indicator to show the condition of the mainspring, two oppositely-facing snail-gears connected to rotate the one with the arbor and 70 the other with the barrel, a toothed gear interposed between and engaging both snail-gears, a reciprocating bar connected with said toothed gear, a rack formed on said reciprocating bar, a pinion engaged by said 75 rack, and connections between said pinion and indicator.

5. In a watch or the like, the combination with the mainspring, and barrel and arbor connected to the opposite ends thereof, of an 80 indicator-hand to show the condition of the mainspring, a wheel connected to the arbor, snail-teeth formed on the facing sides of said wheel and on the barrel-head, a rolling gear interposed between said snail-teeth and en- 85 gaging both, and indicator-actuated means connected to said gear.

6. In a watch or the like, the combination with the mainspring, and going-barrel and winding-arbor connected to the opposite ends 90 thereof, of an indicator to show the condition of the mainspring, a ratchet-wheel connected to the winding-arbor, snail-teeth formed on the facing sides of said ratchet-wheel and barrel-head, and gearing engaging both snail- 95 gears and connected to the indicator.

7. In a watch or the like, the combination with the mainspring, and barrel and arbor connected to the opposite ends thereof, two oppositely-facing snail-gears connected to ro- 100 late the one with the arbor and the other with the barrel, a rolling gear interposed between and engaging both snail-gears, an arm connected to said rolling gear, a sleeve surrounding the seconds-arbor and carrying an 105 indicator-hand and connections between said arm and sleeve to actuate the latter.

8. In a watch or the like, the combination with a mainspring, and a barrel and an arbor connected to the opposite ends thereof, of an 110 indicator to show the condition of the mainspring, two oppositely-facing snail-gears connected to rotate the one with the arbor and the other with the barrel, a rolling gear interposed between and engaging both snail-gears 115 and arranged to move toward the peripheries of said snail-gears when the watch is being wound and toward the centers of said snail-gears when the watch is running, and connections between said rolling gear and the in- 120 dicator.

In testimony whereof I, the said JOSEPH MAZER, have hereunto set my hand.

JOSEPH MAZER.
